UNITED STATES PATENT OFFICE.

ISAAC W. LITCHFIELD, OF WASHINGTON, DISTRICT OF COLUMBIA.

SELECTIVE CARD-INDEX SYSTEM.

1,382,004.

Specification of Letters Patent. Patented June 21, 1921.

Application filed October 24, 1917. Serial No. 198,348.

To all whom it may concern:

Be it known that I, ISAAC W. LITCHFIELD, a citizen of the United States of America, and a resident of Washington, District of Columbia, have invented a new and useful Improvement in Selective Card-Index Systems, which invention is fully set forth in the following specification.

This invention relates to a selective card-index system, and has for an object to provide a system of this type which is simple in construction, inexpensive to manufacture, flexible in use, easy of manipulation, and efficient in operation.

15 A further object of this invention is to provide a system of the type characterized whereby, with the consumption of a minimum of time and effort, classified groups of cards may be readily selected and, if desired, 20 displaced for inspection, and whereby is permitted the use of a relatively large number of classified groups, a more or less complex classification, and the placing of single cards in a plurality of classified groups.

25 Stated broadly, the invention comprises a selective card-index system having a series of cards so constructed, as by the provision of apertures or notches therein, as to provide one or more passages or grooves extending longitudinally of the series. In the form 30 shown, the notches are provided in the edge of the cards to form longitudinally-extending grooves in the edges thereof. As many grooves are provided as there are classified 35 groups and the cards of each group project into a separate groove devoted to that group. Corresponding notches are in substantial alignment when the cards are in exact alignment, but the cards of each classified group

40 have their notches corresponding to the groove devoted to that group slightly offset with respect to the corresponding notches of the remaining cards, so that the cards of said group project into said groove. Means 45 may be provided for engagement in said groove or grooves for displacing the cards which project into the selected groove, such displacement bringing the notches of all the cards corresponding to the selected groove 50 into exact alignment and therefore displacing the cards of the corresponding group with respect to the remaining cards of the series so that the cards of said group may be readily selected.

55 Said grooves may be placed in either one or both horizontal edges of the series of cards

or in one or both vertical edges of the series of cards, or in both vertical and horizontal edges of the series. In either event, the relative location of the notches to their corresponding grooves provides a visual indication of the classification of the respective cards. When more than one edge is used, the grooves in the several edges may be used for the selection of groups made in accordance with the same classification, or the grooves in the several edges may be used for the selection of groups made in accordance with different classifications. Where the grooves are only provided in a horizontal or 60 vertical edge or edges of the series, the vertical or horizontal edges respectively of the cards may be cut to provide tabs for convenience of manipulation or inspection of the selected cards, or such tabs may be used 65 for the purpose of subclassification. The series of cards may be positioned within a container permitting a lateral displacement of the cards, and to facilitate the inspection of the selected group of cards after displacement, means may be provided within the container for projecting the displaced cards 70 of the selected group from the series, as by tilting or elevating the same.

The invention is capable of receiving a 75 variety of mechanical expressions, two of which are illustrated on the accompanying drawing, but it is to be expressly understood that the drawing is for the purposes of illustration only and is not to be construed as a 80 definition of the limits of the invention, reference being had to the appended claims for that purpose.

Referring to said drawing, wherein the same characters of reference designate corresponding parts in the several figures,—

Figure 1 is a plan view of a container provided with a series of cards constructed in accordance with the present invention;

Fig. 2 is a transverse section through the 100 container showing, in full lines, a selected card displaced and, in dotted lines, said card elevated by means within the container;

Fig. 3 is a fragmentary section of the container showing a detail of the card-elevating 105 means;

Fig. 4 is a perspective view of a device for displacing the cards;

Fig. 5 is a perspective view of a card wherein the notches are provided in a vertical edge only.

Referring in detail to said drawing, 1 des-

ignates a series of cards of any suitable size, shape and construction, and designed to receive any desired subject-matter. In the example chosen for illustration, it is assumed 5 that this series of cards comprises three classified groups. In the form shown, each of the cards is provided in its upper edge with three notches of any suitable shape, designated 2, 3 and 4, respectively, the corresponding 10 notches in the several cards being in substantial alinement. When the cards are in exact alinement, these notches, as shown in Fig. 1, provide grooves extending longitudinally of the series, said grooves being designated 15 5, 6 and 7, respectively. All cards of classified group A have their notches 2 offset with respect to the notches 2 in the remaining cards which go to make up groove 5, so that all cards of this group project into 20 said groove, as clearly shown in Fig. 1. Similarly all cards of groups B and C have their notches 3 and 4 respectively offset with respect to the corresponding notches in the remaining cards which go to make up grooves 25 6 and 7 respectively, so that the cards of these two groups respectively project into said respective grooves, as also clearly shown in Fig. 1.

While the projection of all cards of a 30 classified group into the corresponding groove constitutes a ready means for selecting the cards of such group, means may be provided for displacing the cards of the several groups by engagement in any of said 35 grooves, said means being designed to bring all of the notches corresponding to a selected groove into exact alinement. Any suitable means may be employed for this purpose. In the form shown in Fig. 4, a 40 device suitable for use with grooves in the edges of the cards is illustrated. In this construction a pair of plates 8 are bent in opposite directions along lines parallel to their outer edges so as to provide main diverging portions 9 and outer parallel portions 45 10. Said portions 10 are normally maintained in face engagement by a spring interposed between the portions 9, which spring may conveniently take the form of 50 a bow spring 11 riveted to the two plates. Said plates may be hinged together along said lines of bending in any suitable way. In the form shown, the hinge is provided by the use of a pair of screws 12 mounted 55 in one of said plates and loosely engaging in elongated apertures in the other of said plates, said screws being suitably headed over to prevent disengagement of the plates. The outer portions 10 of the plates 8, when 60 in face engagement, must have a combined thickness no greater than the distance between the projecting portions of the cards of a classified group, and the opposite wall of the groove constituted by the corresponding 65 notches in the remaining cards, and pref-

erably have a slightly less combined width. Said outer portions 10, maintained in face contact by the interposed spring, as shown in Fig. 4, may be engaged in any of the grooves 5, 6 or 7, and the portions 9 of said plates 8 then moved toward each other against the tension of the spring 11; the portions 10 are thereby separated (see Fig. 2) and this separation, by engagement with the projecting cards, brings all of the 70 notches in the series of cards corresponding to the selected groove into exact alinement. In order to prevent injury to the cards, the distance between the outer edges of the portions 10 when the portions 9 are in engagement or at their innermost limit of movement should be no greater than the width of the notches in the edges of the cards. Such bringing of all of the notches corresponding to a given groove into exact alinement 80 produces a displacement of all cards which projected into said groove, said displacement causing all of the cards of the particular classified group to project laterally from the series, as shown at 18, Fig. 2. 85 90

The series of cards may be mounted in any suitable container, that shown on the drawing comprising a drawer 14 of usual construction provided with a block or plate 15, which, if desired, may be inclined and 95 which is shown as slidable on a metal strip 16 and carrying the usual spring-pressed locking device 17 for engagement in any one of a series of apertures 18 provided in said strip. Said container may be and preferably 100 is made interiorly of a width sufficient to allow the lateral displacement of the cards therein in the manner above described, i. e., said container is made of an interior width somewhat in excess of the width of the cards 105 plus the extent of displacement.

Means are also preferably provided for projecting the displaced cards from the series, as by elevating or tilting the same, so as to facilitate their inspection. Any suitable means may be employed for this purpose. In the embodiment of the invention shown on the drawing, a plate 19 is positioned at one side of the container and extends throughout the length thereof, being 110 provided, as shown, with a flange 20 projecting inwardly from its lower edge, the width of said flange being no greater, and preferably somewhat less, than the extent 115 of lateral displacement of the cards of a classified group from the series in the manner above described. At its upper edge, said plate 19 is provided with any suitable means for manipulating the same, being shown as provided with a flange 21 of a width somewhat less than the thickness of the lateral wall of the container so as not to interfere 120 with the insertion of the container within its cabinet. Said plate is shown as mounted 125 for limited vertical reciprocation within the 130

container, any suitable means being provided for guiding and limiting the extent of movement of said plate. In the form shown, a pair of angle pieces 22 are suitably secured, one at each end of the container, in a position to overlap the face of plate 19 and guide it in its reciprocating movements, said angle pieces by their engagement with flange 20 also operating as a stop to limit the upward movement of said plate. The friction provided by the engagement of plate 19 with the wall of the container and the angle pieces 22 may be relied upon for retaining said plate in its raised position, or any suitable spring detent may be provided for retaining said plate in its raised position. When means are provided as described for raising the displaced cards, the series of cards is maintained above the bottom of the container, so that when displaced they will overlie the flange 20, by any suitable means as strips 23, of a thickness equal to or greater than the thickness of flange 20, suitably secured to the bottom of the container.

In operation, the series of cards are positioned within the container with one lateral edge in engagement with the corresponding side of the container. When means are provided for elevating the displaced cards, the lateral edge of each card opposite such elevating means is normally in engagement with the corresponding side of the container. The cards being then in exact alinement, the grooves provided by the notches have the appearance shown in Fig. 1, all cards of each classified group projecting into the groove devoted to such group and provided by the corresponding notches in the remaining cards. Assume, now, that it is desired to inspect all cards in group A. The operator may take the manipulative means comprising the two plates 8 and, in their relative position shown in Fig. 4, insert the portions 10 thereof into groove 5 between the projecting cards of class A and the opposite wall of said groove. The portions 9 of said plates are then moved toward each other, correspondingly separating portions 10 of said plates into the position shown in Fig. 2. This operation positively retains all of the cards not embraced in group A with their lateral edges against the inner face of the side of the container and positively displaces all of the cards of group A until the notches 2 therein are brought into exact alinement with the notches 2 in the remaining cards. If there is any tendency for the displacement of the group to produce a tipping of the cards of this group, an angle piece may be laid along the upper corner of the series of cards opposite the card-elevating means, or the cards may be held against tipping by placing the thumb thereon.

65 **The displacement of the cards of group**

A causes all cards of said group to project over flange 20 of plate 19. By raising said plate, all cards of this group may be elevated or tipped into the dotted line position shown in Fig. 2, whereby they may be readily inspected.

In place of notches in the horizontal edges of the cards, the notches may be provided in the vertical edges of the cards as shown in Fig. 5, in which case the container must be made of skeleton construction to permit inspection or insertion of the manipulative means into the grooves provided by the notches in the vertical edges of the cards. Or notches may be provided in both vertical and horizontal edges of the cards. Where notches are provided only in the lateral edges of the cards, additional means for elevating the selected cards becomes unnecessary.

It will therefore be seen that a selective card-index system has been provided whereby all cards of a selected group may be readily identified and, if desired be positively displaced with respect to the remaining cards of the series, while positively retaining all of the remaining cards in their normal position, which system admits of the division of the cards into a large number of classified groups, which classification may be more or less complex, and permits of the placing of a single card in more than one group. Furthermore, it will be perceived that the system is simple in construction and inexpensive to manufacture, and permits a ready selection of all cards of a desired group with a minimum expenditure of time and effort.

While the embodiment illustrated on the drawing has been described with considerable particularity, it is to be expressly understood that the invention is not to be restricted thereto, for it is capable of receiving a variety of mechanical expressions, some of which will readily suggest themselves to those skilled in the art, while certain features thereof are capable of use without other features thereof. Furthermore, while the invention is illustrated as applied to cards in the usual drawer of a card-index cabinet, it is to be understood that the cards may be kept in their original container and the selection performed by inspection or in any suitable manner. Reference is therefore to be had to the claims hereto appended for a definition of the limits of the invention.

What is claimed is:—

1. In a selective card-index system, a series of cards provided with notches in substantial alinement, all cards of a classified group having their notches offset with respect to the notches of the remaining cards whereby the cards of said group project into the groove constituted by the notches in the remaining cards.

2. In a selective card-index system, a series of cards comprising a plurality of classified groups, each of said cards being provided with as many notches in the edge thereof as there are classified groups, the corresponding notches of all of said cards being in substantial alinement, and all the cards of each group having a corresponding notch offset with respect to the alined notches of the other cards whereby the cards of each group project into one of the grooves constituted by alined notches in the remaining cards.

3. In a selective card-index system, a series of cards provided with notches in substantial alinement, all cards of a classified group having their notches offset with respect to the notches of the remaining cards whereby the cards of said group project into the groove constituted by the notches in the remaining cards, and manipulative means for engagement in said groove and operative to positively bring all of said notches into actual alinement whereby to displace the cards of said group with respect to the remaining cards.

4. In a selective card-index system, a series of cards comprising a plurality of classified groups, each of said cards being provided with as many notches in the edge thereof as there are classified groups, the corresponding notches of all of said cards being in substantial alinement, and all the cards of each group having a corresponding notch offset with respect to the alined notches of the other cards whereby the cards of each group project into one of the grooves constituted by alined notches in the remaining cards, and manipulative means for engagement in any of said grooves and operative to bring all of the corresponding notches into actual alinement whereby to displace the cards of the selected group with respect to the remaining cards.

5. In a selective card-index system, a series of cards provided with notches in substantial alinement, all cards of a classified group having their notches offset with respect to the notches of the remaining cards whereby the cards of said group project into the groove constituted by the notches in the remaining cards, a container for said cards permitting lateral displacement of said cards therein, and manipulative means for engagement in said groove and operative to displace laterally the cards of said group with respect to the remaining cards.

6. In a selective card-index system, a series of cards comprising a plurality of classified groups, each of said cards being provided with as many notches in the edge thereof as there are classified groups, the corresponding notches of all of said cards being in substantial alinement, and all the cards of each group having a corresponding notch offset with respect to the alined notches of the

other cards whereby the cards of each group project into one of the grooves constituted by alined notches in the remaining cards, a container for said cards permitting lateral displacement of said cards therein, and manipulative means for engagement in any of said grooves and operative to displace laterally the cards of the selected group with respect to the remaining cards.

7. In a selective card-index system, a series of cards provided with notches in substantial alinement, all cards of a classified group having their notches offset with respect to the notches of the remaining cards whereby the cards of said group project into the groove constituted by the notches in the remaining cards, a container for said cards permitting lateral displacement of said cards therein, manipulative means for engagement in said groove and operative to displace laterally the cards of said group with respect to the remaining cards, and means to elevate the displaced cards with respect to the remaining cards.

8. In a selective card-index system, a series of cards comprising a plurality of classified groups, each of said cards being provided with as many notches in the edge thereof as there are classified groups, the corresponding notches of all of said cards being in substantial alinement, and all the cards of each group having a corresponding notch offset with respect to the alined notches of the other cards whereby the cards of each group project into one of the grooves constituted by alined notches in the remaining cards, a container for said cards permitting lateral displacement of said cards therein, manipulative means for engagement in any of said grooves and operative to displace laterally the cards of the selected group with respect to the remaining cards, and means to elevate the displaced cards with respect to the remaining cards.

9. In a selective card-index system, a series of cards provided with notches in substantial alinement, all cards of a classified group having their notches offset with respect to the notches of the remaining cards whereby the cards of said group project into the groove constituted by the notches in the remaining cards, a container for said cards permitting lateral displacement of said cards therein, manipulative means for engagement in said groove and operative to displace laterally the cards of said group with respect to the remaining cards, and a reciprocating device provided with a flange into operative engagement with which said cards move when displaced laterally.

10. In a selective card-index system, a series of cards comprising a plurality of classified groups, each of said cards being provided with as many notches in the edge thereof as there are classified groups, the

- corresponding notches of all of said cards being in substantial alinement, and all the cards of each group having a corresponding notch offset with respect to the alined 5 notches of the other cards whereby the cards of each group project into one of the grooves constituted by alined notches in the remaining cards, a container for said cards permitting lateral displacement of said 10 cards therein, manipulative means for engagement in any of said grooves and operative to displace laterally the cards of the selected group with respect to the remaining cards; and a reciprocating device provided 15 with a flange into operative engagement with which said cards move when displaced laterally.
11. In a selective card-index system, a series of cards constructed to provide a 20 groove extending longitudinally through all of the series, all cards of a classified group projecting into said groove, and manipulative means for engagement in said groove and operative to displace positively the cards 25 which project into said groove.
12. In a selective card-index system, a series of cards comprising a plurality of classified groups, said cards being constructed at their edges to provide as many 30 grooves extending longitudinally through all of the series as there are groups, all cards of each group projecting into one of said grooves, and manipulative means for engagement in any of said grooves and operative to displace positively the cards which 35 project into said groove.
13. In a selective card-index system, a series of cards constructed to provide a groove extending longitudinally of the 40 series, all cards of a classified group projecting into said groove, manipulative means for engagement in said groove and operative to displace positively the cards which project into said groove; and means to project 45 the displaced cards from the series.
14. In a selective card-index system, a series of cards comprising a plurality of classified groups, said cards being constructed at their edges to provide as many 50 grooves extending longitudinally of the series as there are groups, all cards of each group projecting into one of said grooves, manipulative means for engagement in any of said grooves and operative to displace positively 55 the cards which project into said groove, and means to project the displaced cards from the series.
15. In a selective card-index system, a series of cards provided with notches in substantial alinement, all cards of a classified 60 group having their notches offset with respect to the notches of the remaining cards
- whereby the cards of said group project into the groove constituted by the notches in the remaining cards, and manipulative 65 means for engagement in said groove, said manipulative means comprising members adapted to be separated to displace positively the cards projecting into said groove while positively retaining the remaining 70 cards against displacement.
16. In a selective card-index system, a series of cards, a container therefor permitting lateral displacement of said cards therein, means to displace laterally all cards of a classified group, and means to elevate the displaced cards with respect to the remaining cards.
17. In a selective card-index system, a series of cards, a container therefor permitting lateral displacement of said cards therein, means to displace laterally all cards of a classified group, and means to elevate the displaced cards with respect to the remaining cards comprising a reciprocating device 85 provided with a flange into operative relation with which said cards are displaced.
18. In a selective card-index system, a series of cards constructed at their edges to provide a groove extending longitudinally 90 of the series, all cards of a classified group projecting into said groove, and manipulative means for engagement in said groove, said manipulative means comprising members adapted to be separated to displace 95 positively the cards projecting into said groove while positively retaining the remaining cards against displacement.
19. In a selective card-index system, a series of cards so constructed as to provide 100 a passage extending through all of the series, all cards of a classified group projecting into said passage to such a position that they may be engaged by a displacing device inserted into said passage, and means 105 insertible into said passage for positively displacing the cards projecting into the same.
20. In a selective card-index system, a series of cards comprising a plurality of classified groups, said cards being so constructed as to provide as many passages extending through all of the series as there are classified groups, all cards of each group projecting into one of said passages to such a position that it may be engaged by a displacing device inserted into said passage, and means 115 insertible into any one of said passages for positively displacing the cards projecting into the same.
- In testimony whereof I have signed this specification.

ISAAC W. LITCHFIELD.
